N. E. Gee

Attorney

UNITED STATES PATENT OFFICE.

HARRY B. SHAEFFER, OF ALTOONA, PENNSYLVANIA.

SHOCK ABSORBER.

Application filed November 18, 1921. Serial No. 516,154.

To all whom it may concern:

Be it known that HARRY B. SHAEFFER, a citizen of the United States, residing at Altoona, in the county of Blair and State of Pennsylvania, has invented certain new and useful Improvements in Shock Absorbers, of which the following is a specification.

This invention relates to motor vehicles and has for its primary object an improved shock absorber, having means for preventing the violent reaction of the vehicle springs after the same have been suddenly deflected as a result of operating the car, to which it is attached, over rough or uneven roads.

Another object of this invention is to provide means of increasing or decreasing the resistance offered by the shock absorber, such as to make the same readily applicable to cars of different weights.

A further object of this invention is to provide an improved means for releasing the tension on the spiral spring which forms the primary element of the shock absorber, as well as improved means for increasing the tension on said spring.

A still further object of the invention is to provide a suitable casing for the shock absorber, such that all the operating parts are contained therein, will be free from the road dirt in a compact housing that is readily attached to the car frame.

With these and many other objects in view which will be more readily apparent as the nature of the invention is better understood, the same consists in the novel construction, combination, and arrangement of parts as will be hereinafter fully pointed out illustrated and claimed.

It will be quite readily understood by those skilled in the art to which this invention belongs that same is susceptible to a variety of structural changes and modifications without departing from the spirit or scope of the invention, but a preferred and thoroughly practical embodiment of the invention is shown in the accompanying drawings in which—

Figure 1 shows a section of a front automobile axle together with a front spring and a portion of the frame, having my present invention applied thereto.

Figure 2 shows a sectional elevation of the shock absorber having the top of the casing removed.

Figure 3 shows a sectional end view of the parts shown in Figure 2 of the drawings.

Figure 4 shows an elevational view of the shock absorber casing, having therein a slightly different form of friction increasing device from that shown in Figure 2 of the drawings.

Figure 5 shows an edge view of the arrangement shown in Figure 4 of the drawings.

Similar reference numerals refer to similar parts throughout the several figures of the drawings.

In carrying out this invention no change is contemplated in the usual construction of the automobile to which this device may be attached, and to this end there is provided a casing designated by the numeral 10, which is adapted to be attached to a frame 11 of an automobile, having the usual axle 12 and semielliptical spring 13, attached thereto.

The axle 12 is provided with a clamp designated by the numeral 14, to which is attached one end of a flexible cord 15, while the other end is adapted to engage a clevis 16 to which is attached a pulley 17 which is shown positioned within the housing in Figure 2.

Coacting with the pulley 17 is a flexible band 18, one end of which is fixedly positioned on a pin 19 in the casing 10, while the other end is adapted to pass around a rotatable casing 20 and attached thereto, as shown in Figure 2 of the drawings.

The casing 20 is provided therein with a spiral wound spring 21, one end of which is secured to the neck extension of a ratchet bearing 22.

The neck 23 is provided with a slot 24 into which the end 25 of the spiral spring 21 is adapted to be positioned. The ratchet 22 is secured to an operating shaft 26 which projects through a cover plate 27, and also rests in bearing 29 provided as an integral part of the casing 10.

The cup shaped housing or drum 20 is provided with a cover plate 30 which is held in position by a collar 31, engaged by a ledge 32 on the ratchet bearing 22 as shown in Figure 3 of the drawings.

For the purpose of increasing the tension on the spiral spring the end 28 of the shaft 26 is made square in order to readily take a wrench by which the shaft 26 is adapted to rotate.

The ratchet 22 being secured to the shaft 26 by means of a pin 34, rotation of the shaft rotates the collar or neck 23 and winds the spring on the neck 23, thus the spring tends to rotate the disk to which the band 18 is attached.

For the purpose of holding the spiral under the desired tension a pawl 35 is positioned on a pin 36 and held in engagement 10 with the ratchet by a spring 37 which is positioned on a bracket 38 and is adapted to fulcrum against a bracket 39.

For the purpose of relieving the tension on the spiral spring a pawl lifting device is 15 provided, which is adapted to be operated with a wrench such that the finger 40, which engages the tail 41, of the dog will overcome the effort exerted by the spring 37, and with a wrench applied to the end 36 of the winding shaft the tension can be adjusted to suit.

A stop 42 is provided and is adapted to be engaged by a finger 43, when the pawl is released from the teeth in the ratchet.

When it is desired to apply this type of 25 shock absorber to a heavy car and additional shock absorbing means are needed, the scheme in Figure 4 is proposed, and consists of a plurality of pulleys 17^a over which the flexible band 18^a is adapted to pass, each pulley

the band passes over adds to the dampening 3 action of the device.

Having thus described my invention what I claim and desire to secure by Letters Patent—

1. A shock absorber including a casing, a 35 spring tensioned drum supported therein, a stationary post within the casing, a flexible band attached to said spring tensioned drum and to the post, and a floating pulley resting in the bight of said band between the post 40 and the drum, and means for connecting the pulley with a vehicle part.

2. A shock absorber including a casing, a 45 spring tensioned drum rotatably supported therein, a stationary post within the casing, a flexible band attached to said spring tensioned drum and to the post, a plurality of stationary idler pulleys over which the band passes between the spring tensioned drum and the post, a floating pulley engaging in a 50 bight of said band formed between the last mentioned stationary pulley and the post, and means for connecting said floating pulley with a vehicle part.

In testimony whereof he affixes his signature. 55

HARRY B. SHAEFFER.
